DESIGN FOR A STOCKING

Lucile J. Maclear, New York, N. Y., assignor to Van Raalte Company, Inc., New York, N. Y., a corporation of New York

Application February 6, 1934, Serial No. 50,635

Term of patent 7 years

To all whom it may concern:

Be it known that I, LUCILE J. MACLEAR, a citizen of the United States of America, residing in the city, county, and State of New York, have invented a new, original, and ornamental Design for Stockings, of which the following is a specification, reference being had to the accompanying drawing forming a part thereof.

In the drawing:

a portion of the foot and sole of the stocking shown in Figure 1, illustrating the detailed design on a larger scale.

The novel portion of my design is the open-work ornamentation running horizontally along the foot and toe of the stocking, the details of which are more clearly shown in Fig. 2.

I claim:

The ornamental design for a stocking substantially as shown and described.

LUCILE J. MACLEAR.
